J. RAGGIO ET AL.
RECEPTACLE,
FILED JAN. 26, 1922.

1,447,035.

UNITED STATES PATENT OFFICE.

JAMES RAGGIO AND FRANK BONGIORNI, OF BROOKLYN, NEW YORK.

RECEPTACLE.

Application filed January 26, 1922. Serial No. 531,934.

To all whom it may concern:

Be it known that we, JAMES RAGGIO and FRANK BONGIORNI, citizens of the United States, and residents of the city of New York, borough of Brooklyn, in the county of Kings and State of New York, have invented a new and Improved Receptacle, of which the following is a full, clear, and exact description.

10 This invention has relation to receptacles and has particular reference to a receptacle for water or liquids provided with means for cooling and maintaining the contents cold.

One of the principal objects of the present invention resides in the provision of a receptacle for drinking water which includes a separate compartment for ice as a cooling medium, whereby the practice of placing the ice directly in the water is eliminated.

20 As a further object the invention aims to provide means for receiving and drawing off the water resulting from the melting of the ice from the remainder of the ice without the necessity of emptying the receptacle 25 proper.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawing—

Figure 1 is a side elevation of a receptacle constructed in accordance with the invention.

40 Fig. 2 is a transverse sectional view thereof taken approximately on the line 2—2 of Fig. 1.

Referring to the drawings by characters 45 of reference, 10 designates a receptacle such as a pitcher, bottle, or other similar article, which in the present instance is especially designed to contain drinking water or any other drinking fluid. The receptacle 10 is 50 provided with a centrally disposed chamber 11 having a reduced central outlet 12 in the bottom 13 which establishes communication with a subterposed chamber 14 occupying the space between the bottom 13 of the chamber 55 11 and the bottom 15 of the receptacle 10. The chamber 14 is provided with an outlet 16

through a threaded neck 17 over which a closure cap 18 is normally arranged. The upper end of the chamber 11 terminates in a laterally bent neck 19 which extends through the side of the receptacle 10 to provide an exteriorly threaded filling nozzle 20 upon which a closure cap 21 is mounted. In practice the water or other drinking fluid A is received in the receptacle 10 and ice indicated at B is placed in the chamber 11 to provide a cooling agent for cooling and maintaining the contents A at the required temperature. The drain water indicated at C will be discharged from the chamber 11 60 through the outlet opening 12 in order to prevent collection of the drain water in the receptacle 11 which might tend to counteract the cooling action of the ice and hasten the melting of the same. When the chamber 14 is filled with drain water C, the closure 18 65 may be removed to permit of the drawing off of the same from the chamber 14 without emptying the contents from the receptacle 10.

By this construction it will be seen that a receptacle is provided for drinking water or other drinking fluids which affords means for receiving a cooling agent for the contents thereof in order that said cooling agent may 70 be separated therefrom. The device will be found especially useful in private homes, sick rooms, hospitals, restaurants, or other public places, to afford a receptacle for cold beverages, and this without impairing the 75 quality of the beverage by the elimination of the common unsanitary practice of placing ice of unknown quality directly in the beverage.

We claim:

1. A receptacle for liquids comprising a cylindrical body having a convex bottom, an integral cylindrical member extending upwardly from said bottom with the upper end turned laterally and extending through the side of said body below its upper end, a horizontal partition in the central member having an aperture establishing communication between the upper portion of the member and the lower portion thereof and subdividing said receptacle into an outer receiving compartment for the liquid, an interior upper ice receiving compartment and a lower interior drain water chamber, an outlet nozzle for the drain water chamber extending 100 below the central portion of the bottom and lying within the concavity formed at the 105 bottom of the receptacle.

underside thereof, a cap for closing said outlet nozzle, and a cap for closing the extremity of the laterally turned portion of the central member which extends through the side of the receptacle.

2. As a new article of manufacture, a water pitcher comprising an outer body, an integral receptacle extending upwardly from the bottom thereof having the upper portion thereof extending through the side of the outer body, a horizontal partition in said inner receptacle provided with a restricted passage communicating with the space be-

low the partition, an opening in the bottom of the receptacle communicating with the space below the partition, and a closure cap therefor, the said inner receptacle adapted to receive ice above the partition, the space below the same adapted to receive the drain water from the ice, and the opening in the bottom constituting means for withdrawing the drain water without the necessity of emptying the pitcher of its contents.

JAMES RAGGIO.
FRANK BONGIORNI.
